UNITED STATES PATENT OFFICE.

JOHN B. DAVIS, OF CLEVELAND, OHIO, ASSIGNOR TO THE W. S. TYLER COMPANY, OF CLEVELAND, OHIO, A CORPORATION OF OHIO.

ELEVATOR-DOOR-OPERATING DEVICE.

1,198,896.

Specification of Letters Patent. Patented Sept. 19, 1916.

Application filed May 4, 1916. Serial No. 95,325.

To all whom it may concern:

Be it known that I, JOHN B. DAVIS, a citizen of the United States, and a resident of Cleveland, in the county of Cuyahoga and State of Ohio, have invented a new and useful Improvement in Elevator-Door-Operating Devices; and I do hereby declare the following to be a full, clear, and exact description thereof.

10 My invention pertains to elevator-door operating devices, and is particularly applicable to the type of elevator closure in which the doors slide away from one another, to leave a central opening, when the 15 same are opened.

It is the principal object of my invention to improve upon the devices heretofore employed for causing one of the doors to move in one direction when the other is moved in 20 the opposite direction.

It is another object of my invention to provide a simple, economical, efficient and compact device for opening one elevator door from another, to cause such door to be moved forward and backward whenever 25 the other door is similarly moved. And other and further objects of my invention will become clear from the specification taken in connection with the annexed claim.

30 By way of example, I have described in the following specification, and shown in the accompanying drawing, a form of elevator-door operating device constructed in accordance with my invention. Changes, 35 however, may be made in the construction shown and described, without exceeding the scope of the invention, as defined in the appended claim.

In the drawing: Figure 1 is a front view 40 of an elevator doorway, provided with a door operating device constructed in accordance with my invention; Fig. 2 is a plan of the door operating device; Fig. 3 is an enlarged front view of the center sprockets; and Fig. 4 is a sectional plan of the 45 same, the section being taken at the line *a—a* of Fig. 3.

Throughout the following specification, like reference characters indicate like parts 50 in referring to the several figures of the accompanying drawing.

Referring now to the drawing, 10 and 10^a designate a pair of elevator doors, each having hangers 11 carrying rollers 12. These

rollers run on a track 13 which is provided 55 at the top of the doorway; so that, by moving the doors 10 and 10^a away from each other, the same are opened, and are likewise closed by moving them toward each other.

Secured to the door frame, at or near the center thereof, is a bracket 13^a, in which is mounted a spindle 14, which carries a pair of sprockets 15 and 16 respectively. Somewhat beyond the ends of the doors, when the latter are in their closed position, the 65 door frame is also provided with brackets 17 and 18, which carry sheaves or sprockets 19 and 20. A chain 21 passes around the sprocket 19 and the sprocket 15; and a chain 22 passes around the sprocket 20 and the 70 sprocket 16. It will be seen from this that if one of the chains is moved in either direction, the other chain will move in the same direction.

The hangers 11 of the doors 10 and 10^a 75 are connected by cross bars 23, the cross bar 23 of the door 10 being connected to the lower part of the chain 22, and the cross bar 23 of the door 10^a being connected to the upper part of the chain 21.

80 From the above, it will be seen that when the door 10 is moved to the left,—to open the same,—it will cause, through the chain 22, a clockwise rotation of the sprocket 16. The sprocket 16 will effect a corresponding 85 rotation of the sprocket 15, which will cause a movement of the upper part of the chain 21 to the right, such movement being proportionate in extent to the movement of the lower part of the chain 22 to the left. Thus 90 the door 10^a, which is connected to the upper part of the chain 21, will be moved to the right at the same speed, and to the same extent, as the door 10 is moved to the left. Suitable devices, such as those indicated at 95 24, may be provided for taking up any slack in the chains.

The door-operating device of my invention is extremely simple in construction, as well as being compact and presenting no 100 parts which are liable to get out of order. Moreover, it is positive in its function of causing either door to move proportionately to the other door. It does not present any slack chain at the center of the doorway, as 105 has been the case in previous constructions wherein a single chain extending the entire width of the doorway has been employed.

Having thus fully described my invention, what I claim as new, and desire to secure by Letters Patent, is:

The combination with a pair of doors, 5 slidable toward and away from each other to close and open the door way, of a pair of chain sprockets connected co-axially with each other and disposed substantially centrally between said doors, a pair of endless 10 chains coöperating one with each of said sprockets, and extending in opposite direc-

tions therefrom, means for connecting one of said doors to the lower part of one of said chains, and means for connecting the other door to the upper part of the other 15 chain.

In testimony whereof I, the said JOHN B. DAVIS, have hereunto set my hand.

JOHN B. DAVIS.
